MICROPHONE CASING

Louis R. Burroughs, Buchanan, Mich.

Application March 30, 1954, Serial No. 29,764

Term of patent 14 years

(Cl. D26—14)

Fig. 2.

Fig. 1.

Fig. 3.

Fig. 4.

Fig. 5.

To all whom it may concern:

Be it known that I, Louis R. Burroughs, a citizen of the United States, residing at Buchanan, county of Berrien, Michigan, have invented a new, original, and ornamental Design for a Microphone Casing, of which the following is a specification, reference being had to the accompanying drawing, forming a part hereof.

Figure 1 is a side view of a microphone casing, the other side being similar;

Figure 2 is a front view;

Figure 3 is a rear view;

Figure 4 is a bottom view; and

Figure 5 is a top view.

The dominant features of my design reside in those portions shown in full lines.

I claim:

The ornamental design for a microphone casing, as shown and described.
